UNITED STATES PATENT OFFICE.

WILEY GRADICK, SR., OF TYLER, TEXAS, ASSIGNOR TO WOLDERT GROCERY COMPANY
(INCORPORATED).

NUTCRACKER.

1,248,313.

Specification of Letters Patent. Patented Nov. 27, 1917.

Application filed June 28, 1917. Serial No. 177,546.

To all whom it may concern:

Be it known that I, WILEY GRADICK, Sr., a citizen of the United States, residing at Tyler, in the county of Smith and State of Texas, have invented certain new and useful Improvements in Nutcrackers; and I do declare the following to be a full, clear, and exact description of the invention, such as will enable others skilled in the art to 10 which it appertains to make and use the same.

This invention relates to certain new and useful improvements in nut crackers.

The primary object of the invention is 15 to provide a nut cracker having a pair of coöoperating jaws with means for quickly and accurately adjusting one of the jaws with respect to the other to accord for the variations of the size of the nuts to be cracked, said adjustment being entirely independent of the means for forcing one of the jaws into the engagement with the nut.

Another object of the invention is to provide a device of this character which is 20 made of a comparatively few parts, one of the members being a body member composed of a base portion and a tubular portion, these two portions being integrally formed from a single strip of flat material.

30 A further object of the invention is to generally improve upon devices of this class by the provision of an extremely simple, strong, durable and inexpensive construction, one which will be efficient and reliable in operation, and well adapted to the purpose for which it is designed.

With these and numerous other objects 35 in view, the invention consists of certain novel features of construction, and the combination and arrangement of parts as will be hereinafter fully described and claimed.

In the accompanying drawings forming 40 a part of the application, and in which 45 similar reference characters designate like parts throughout the several views,

Figure 1 is a front elevation of the device 50 constructed in accordance with this invention;

Fig. 2 is a side elevation thereof;

Fig. 3 is a central vertical sectional view 55 of the device;

Fig. 4 is a transverse sectional view 60 taken on the plane indicated by the line 5 4—4 of Fig. 1;

Fig. 5 is a perspective view of the body member; and

Fig. 6 is a similar view of the nut member.

Referring more particularly to the drawings, it will be seen that the body member of the improved nut cracker is composed of a base portion 1 and a substantially tubular shank portion 2. These two portions are integrally united with each other, being 65 formed from a single strip of flat material. The shank portion of the strip is disposed substantially at the right angles to the base portion and is bent into tubular form a short distance from the latter. The tubular portion 2 is provided with a longitudinal slot 3 which is open at its end disposed adjacent the base portion 1 and is provided at one of its edges with a series of teeth 4. The base portion 1 is provided with a suitable socket or recess 5, the latter being disposed substantially in alinement with the axis of the tubular portion for a purpose 70 to be hereinafter described.

Disposed within the tubular portion 2 and 75 slidable longitudinally in the same is a tubular nut member 6. On one of the sides of the nut member 6 is fixed in any suitable manner a strip 7 having a projection or a series of teeth 8 formed on one edge thereof and adapted to engage the teeth 4 to 80 lock the nut member in any one of its adjusted positions. Projecting outwardly from the nut member is a lug 9, which constitutes 85 a handle member to be engaged when turning the nut member to engage or disengage the teeth 8 from the teeth 4.

The reference numeral 10 designates a screw having threaded engagement with the above mentioned nut member. This 90 screw 10 is provided with a cross handle 11 at its upper end, and a head 12 at its lower end. The head 12 is to be connected to the screw 10 in any convenient manner, and is preferably to be provided with a recess. Inasmuch as the tubular shank portion 2 of the body member has its axis in alinement with this socket or recess in the base portion of the body member, the recess in the head will be disposed in alinement with said recess in said base portion. 95

In using the device constructed as above described, a nut is placed substantially longitudinally with respect to the body member with one of its ends disposed in the 100 105 110

socket or recess arranged in the base portion 1. The nut member is then moved longitudinally in the tubular shank portion 2 so as to bring the head fixed to the screw 5 in contact with the other end of the nut, said other end of the nut being received in the socket formed in said head. The nut member is then turned so as to cause its teeth to engage with the teeth formed upon 10 the tubular shank portion. This obviously locks the nut member against movement with respect to the body member so that upon turning the screw the head of the same will be caused to engage the nut and crush 15 or crack it. It is to be particularly noted that by having the nut member adjustably mounted with respect to the body member a quick and accurate adjustment may be made to accord for the variations in size 20 of the nuts.

From the foregoing description, taken in connection with the accompanying drawings, the construction, use and operation of the device will be readily understood with 25 out a more extended explanation.

As various changes in the form, proportion, and in the minor details of construction, may be made without departing from the spirit of this invention, it is to be understood that I do not wish to be limited to the precise construction herein shown and described.

I claim:

1. A device of the class described comprising a body member composed of a base

Copies of this patent may be obtained for five cents each, by addressing the "Commissioner of Patents, Washington, D. C."

portion and a tubular shank portion integrally connected therewith, said tubular shank portion being provided with a longitudinal slot having a series of teeth formed on one edge, a nut member movably disposed within said tubular shank portion and provided with a projection to engage said teeth, and a screw having threaded engagement with said nut member and provided with a head at one end thereof disposed in alinement with said base portion to coöperate therewith.

2. A device of the class described comprising a body member composed of a base portion and a tubular shank portion integrally united therewith said tubular shank portion being provided with a longitudinal slot having a series of teeth formed on one edge, a tubular nut member disposed within said tubular shank portion, and a strip fixed to one side of said nut member and disposed in said slot, and provided with a series of teeth at one edge to engage the first mentioned teeth, and a screw having threaded engagement with said nut member and provided with a head at one end disposed in alinement with said base portion to coöperate therewith.

In testimony whereof I have hereunto set my hand in the presence of two subscribing witnesses.
